Attorney

UNITED STATES PATENT OFFICE.

WILLIAM S. ELTERS, OF DAYTON, OHIO, ASSIGNOR TO THE GEM METAL SHIELD, INC.,
OF DAYTON, OHIO, A CORPORATION OF OHIO.

AIR MOISTENER.

Application filed January 16, 1928. Serial No. 247,184.

My invention relates to heating and ventilating, and more particularly to a humidifier or water reservoir to be suspended behind a steam or hot water radiator for moistening 5 the warm air.

It is more or less common practice to support a water reservoir or humidifier behind a radiator in the narrow space between the radiator and the wall of the room and at a 10 level a considerable distance below the top of the radiator. This makes the reservoir quite inconvenient to refill and hence such reservoir or humidifier becomes quite hot through contact with the radiator and it can- 15 not be readily removed for replenishing the water supply. The present invention affords a filling tube telescopically mounted in the reservoir or humidifier, which may be withdrawn therefrom to sufficient extent to 20 project above the top of the radiator and which will serve to direct the water supply into the reservoir. Stop means is provided for limiting the sliding or telescopic movement of the filling tube. When not in use 25 such filling tube is depressed within the reservoir.

The object of the invention is to simplify the means and mode of filling humidifiers or water reservoirs suspended upon radiators without the necessity of removing the reservoir and to provide a telescopic filling tube therefor, by which the reservoir may be filled without spilling.

A further object of the invention is to 35 provide improved means for connecting the filling tube with the reservoir and for mounting and sliding such tube therein.

With the above primary and other incidental objects in view as will more fully 40 appear in the specification, the invention consists of the features of construction, the parts and combination thereof, and the mode of operation, or their equivalents as herein- 45 after described and set forth in the claims.

In the accompanying drawings wherein is 50 shown the preferred, but obviously not necessarily the only form of embodiment of the invention, Fig. 1 is a perspective view of a radiator to which a water reservoir or hu- 55 midifier as herein described has been applied. Fig. 2 is a perspective view of the reservoir or humidifier removed from the radiator. Fig. 3 is a detail sectional view 60 illustrating the mounting of the tube and its 65 range of adjustment.

Like parts are indicated by similar characters of reference throughout the several views.

Referring to the accompanying drawings, 1 is the radiator, upon the back of which is 60 suspended the water reservoir or humidifier 2. This humidifier comprises a tank of rather narrow but deep proportions, one wall of which is angularly corrugated forming a series of spaced bays to project intermediate 65 succeeding radiator sections in order that the reservoir may approximately conform to the radiator 1, presenting a heating surface of increased area in close relation thereto. The reservoir or humidifier is suspended 70 from the top of the radiator by hook arms 3. These arms 3 are attached to the reservoir 2 and engaged with the radiator structure to support the reservoir or humidifier in a suspended position well below the top 75 of the radiator. Inasmuch as the radiator is ordinarily set in close relation with the side wall of the room, the humidifier or reservoir 2 hangs in a rather narrow space in which it is not easily accessible for replenishing of 80 the water supply. Because the humidifier or reservoir is ordinarily heated to a high degree due to its close association with the radiator 1 it cannot be safely removed from such position without danger of burning the 85 fingers of the operator. Such humidifier reservoir per se forms no part of the present invention which pertains primarily to means for conveniently and safely replenishing the water supply of the reservoir.

To facilitate the filling of the reservoir or humidifier 2 and avoid the danger of spilling the water or burning the fingers of the operator, there is provided a filling tube 4 of substantially triangular contour conforming to one of the angular corrugations of the reservoir or tank 2, within which it is longitudinally slidable. This filling tube is normally positioned within the reservoir or humidifier 2 with its lower end resting upon 95 the bottom of the reservoir and its top extending substantially level with the top thereof. The upper end of the tube 4 is provided with a bail 5 which may be engaged by a hook or other device for lifting the 100 tube 4. The tube 4 is withdrawn from the reservoir when it is desired to replenish the water supply. When so extended the upper end of the tube will project substantially 105 level with, or preferably slightly above the 110

level of the top of the radiator 1. In this position, water can be easily and accurately poured into the top of the filling tube 4, by which it is conducted into the reservoir 2 without danger of spilling. The reciprocating filling tube 4 is provided with a stop shoulder 6 adjacent to its lower end which engages with an inturned margin or flange 7 at the top of the angular corrugation within which the filling tube performs its telescopic movement. Such engagement of the stop shoulder 6 with the inturned flange 7 limits the withdrawal of the tube and insures ample overlapping engagement when the tube is extended to prevent spilling the water over the side of the reservoir.

From the above description it will be apparent that there is thus provided a construction of the character described, possessing the particular features of advantage before enumerated as desirable, but which obviously is susceptible of modification in its form, proportions, and arrangement of parts, without departing from the principle involved or sacrificing any of its advantages.

While in order to comply with the statute the invention is described in language more or less specific as to structural features it is to be understood that the invention is not limited to the specific details shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. The combination with a reservoir, one side of which is singularly corrugated to approximately conform to the side of a steam or hot water radiator and having an open top, of a triangular filling tube slidably engaged in one of the angular corrugations, a stop on said tube, and an inturned flange upon the engaged corrugations of the reservoir limiting the withdrawal of the tube therefrom, a bail connected with the top of

said tube to facilitate its withdrawal from the reservoir, said tube being open at its opposite ends and when extended reaching approximately to the top of the radiator upon which the reservoir is supported, for convenience of filling the reservoir there-through.

2. The combination with a reservoir having means for supporting it beside a steam or hot water radiator, of a filling tube open at its opposite ends telescopically projecting within the reservoir and reaching approximately to the top of the reservoir when extended through which water may be conveniently introduced into said radiator, said tube having sliding engagement with the side wall of the reservoir and being retractable within the reservoir when not in use.

3. The combination with a reservoir for mounting upon the side of a steam or hot water radiator having a vertical guide recess formed in a lateral wall thereof of an extensible and contractable filling tube for said reservoir slidably engaged within the vertical guide recess, which, when extended reaches approximately to the top of the radiator and when retracted is substantially concealed within the reservoir.

4. The combination with a reservoir and suspension members therefor for supporting the reservoir in dependent position from the top of a steam or hot water radiator of a filling tube for the reservoir the length of which is approximately equal to that of the reservoir suspension members, the wall of the reservoir being formed into an outwardly projecting bay, said tube being slidably engaged within said outwardly projecting bay of the reservoir for longitudinal movement in a vertical direction relative thereto by which the upper end of the tube is projected into proximity to the top of the radiator for convenience in filling the reservoir through said tube.

In testimony whereof, I have hereunto set my hand this 28th day of December A. D. 1927.

WILLIAM S. ELTERS.
